SPORTING GUN

Paul Scholberg, Liege, Belgium

Application June 27, 1932, Serial No. 619,585
In Belgium February 26, 1932

7 Claims. (CL. 42—16)

This invention relates to sporting guns for instance of the double-barrel type, especially of the so called under- and over barrel type.

According to the present invention the barrels 5 are fixed at their rear or breech end to a housing in the stock, wherein a sliding breech block, adapted to carry locking and striker mechanisms and an operating lever therefor, is located.

An application of the present invention to an 10 under-and-over gun is shown in the accompanying drawings, wherein:—

Figure 1 is an elevation showing the assembled gun with the breech closed.

Figure 2 is a sectional elevation and

15 Figure 3 an end elevation of the breech housing.

Figure 4 is a side elevation and

Figure 5 an end elevation of the sliding breech block.

20 Figure 6 is an elevation of the breech end of the barrels according to one form of construction.

Figure 7 is a section along the line 7—7 Figure 1.

25 Figure 8 is an underside plan of Figure 4.

Figure 9 a central sectional elevation of the breech block and housing, the firing mechanism being uncocked and the breech closed.

30 Figure 10 is a similar view to Figure 9 but showing the firing mechanism cocked and the breech open.

Figure 11 is a plan of the breech block and its housing showing their relative positions when the breech is closed.

35 Figure 12 represents a composite view of the breech-block of Figure 4 in side elevation with the lock raised to release position and arranged in operative position in the breech housing of Fig. 2 shown in section.

40 The gun shown in the accompanying drawings comprises a stock on the forward or breech end of which is mounted an approximately U-sectioned housing 1, a sliding breech 3 housed therein and the barrels which are carried in a block

45 2 rigidly, but removably, fixed to the end of said housing. The sliding breech block 3 is, approximately L-shaped, the shorter limb being disposed vertically within the housing 1, whilst the longer limb extends rearwardly away from the 50 barrels and is adapted, when the breech is open, to extend rearwardly behind the said housing.

An operating lever 4 is pivoted to the upper part of the breech block at its end 5 remote from the said barrels and on the free end 13 of said 55 lever are suspended two arms or keys 10.

The connection between the lever 4 and the keys 10 is effected by a pin 12 passing through the former and engaging in inclined slots in the upper ends of the latter; each of the keys is provided with two lugs 9, 11, located one above the other with a space between them, whilst the block 3 is provided on either side with a horizontal rib 45; the purposes of said lugs 9, 11 and ribs 45 will be described later.

The lever 4 is provided on its underside and 65 intermediate its extremities with a hook or nose 30, which is adapted to engage on the underside of a nose 29 formed on the upper half of for instance one cocking lever 27 pivoted at 28 intermediate its extremities, to the horizontal limb of the breech block 3; the lower part 31 of said lever 70 extends downwardly and is located within a slot or recess 32 in the two parallel strikers or percussion pins 33 disposed in the same horizontal plane and slidably housed within the said limb of the 75 breech block 3 and controlled by coil springs 35. The said strikers 33 extend rearwardly to the end of the breech block remote from the barrels and each is provided on its rearward extremity with a hook or recess 34, each of said hooks or 80 recesses being adapted to be engaged, when the block is pushed backwards in the housing 1, by a nose 38 on the upper portion of a tumbler 37, pivoted at 36 intermediate its extremities to the 85 rear end of the horizontal limb of the breech block 3; the lower portions 39 of the said tumblers 37 contact when the breech is closed with levers 40 pivoted at 41 to the stock, which levers impinge on the triggers 42, 421 in such a manner that when said triggers are pulled the tumblers 37 are 90 tripped to disengage their noses 38 from the recesses or hooks 34, to permit of the strikers being impelled forwardly by the springs 35, whose fixed ends bear against the wall 43.

A leaf spring 25 is fixed upon the top of the 95 breech block, the free end of which spring bears at 26 on the trip or cocking lever 27 and when the lever 4 is raised, applies a force to the said lever, through the contacting noses 29, 30, which tends to return said lever to its lowered position.

100 The breech housing 1 is formed on its internal surface with two horizontal grooves 6 extending throughout its entire length, said grooves being intersected towards their forward ends by vertical grooves 7 extending from top to the bottom 105 of each side of the housing 1, whilst internally of the extreme forward end of said housing are a number of parallel ribs 18 which are located in vertical planes and except where they intersect with the horizontal grooves 6, extend around the 110

entire internal periphery of the housing. Finally horizontal grooves 15 are formed externally of the upper and breech end of the housing 1 where-in the ears 17 of a strap 16, extending across the open top of said housing, engage to permit of the strap being reciprocated in the said grooves.

The breech end 20 of the barrel block 2 is provided with a plurality of parallel ribs 19 disposed in vertical planes which are adapted to fit or 10 engage between the ribs 18 in the breech end of the housing 1.

To assemble the sliding breech block 3 and barrel block 2 to the housing 1, the rearward end of the breech block is inserted into the open 15 breech end of the housing so that the ribs 45 engage with the grooves 6; the block is then pushed into the housing until the lugs 9, 11, on the keys 10 strike against the edges thereof, whereupon the lever 4 is raised to bring the lugs 20 11 above the top edge of the housing and the lugs 9 into the plane of the slot 6 whereupon the sliding of the block 3 can be continued until the lugs 9, 11, are brought into plane of the vertical grooves 7. During this latter rearward movement the lugs 9 are forced on to the lower edges 25 8 of the grooves 6 by the spring 25 acting through the operating lever 27, cocking lever 4 and keys 10, hence immediately the lugs are brought into the plane of the grooves 7 they drop vertically 30 downwards and the breech block is locked in position by virtue of the lugs 9 and 11 bearing against the lateral walls of the grooves 7.

The strap 16 is next fitted onto the forward end of the housing 1 and is pushed backwards a 35 sufficient distance to permit of the insertion of the brush end of the barrel block 2 vertically downwards into said housing so that the ribs 19 may engage between the ribs 18. The strap 16 is then pushed forwards so that it bears on the 40 solid upper end 20 of the barrel block 2, which latter is thereby locked rigidly in position.

The gun is loaded by raising the lever 4 where-upon the lugs 9 are again brought into alignment with the grooves 6, to permit of the breech block 45 being slid rearwardly within its housing, and the nose 30 strikes against the nose 29 and turns the trip or cocking lever 27 in an anti-clockwise direction, the lower end 31 strikes against the rear faces of the recesses 32 in the strikers 33 and 50 forces the latter backwards until the recesses or hooks 34 engage with the tumblers 37 and retain same against the action of the springs 35. When the rear edge of the vertical limb strikes against the end wall of the housing 1, cartridges may be 55 inserted into the breeches of the barrels, where-upon the breech block is slid forward until the lugs 9 and 11 are brought into alignment with the grooves 7 and the block 3 is locked in position.

The keys 10 instead of having a sliding connection with the end 13 of the lever 4, may be fixed thereto, in which case the said keys and also the grooves 7 will be curved and the axes thereof will form arcs of a circle whose centre is located at the pivot pin 5, all as shown in Figure 12.

Figure 5 of the drawings shows how the forward ends of the pins 33 are provided with transverse arms 45', 46, which are provided with the percussion pins proper 47, 48, located, for instance, in the prolongation of the longitudinal axes of the 60 barrels. The head portion of the breech block 3 may be provided with slots or cavities 49, 50 with-in which are located and slide said arms 45, 46.

The tumblers 37 are resiliently held in the position shown in Figures 15 and 16 by springs 51 and 75 stops 52.

The strap 16 may be retained in its operative position for instance by means of a little screw (not shown) passing for instance through the strap and engaging into the barrel-block or into the wall of the breech housing.

The breech-block 3 may be provided with any kind of cartridge-shell-extracting means, for instance with elastic hooks of the kind employed as extractors in automatic pistols.

Finally, it is obvious that the object of the present invention described above may as well be adapted to single barrel guns and to multiple barrel guns other than that shown in the drawings.

What I claim is:

1. A sporting gun comprising a breech-housing having its opposed inner side walls formed with a pair of opposed longitudinal grooves disposed in the same plane and a pair of opposed vertical grooves disposed in the same plane and respectively intersecting the respective horizontal grooves, in combination with a sliding breech-block adapted to be slidably mounted in and removed from said breech-housing, said breech-block having its sides respectively formed with vertical grooves adapted to register in a transverse direction with the vertical grooves in said breech-housing, an operating lever pivotally mounted at its rear end portion on said breech-block, a pair of locking keys connected to the free end of said lever to move therewith and respectively slidably disposed in the respective grooves in said breech-block, each said key being formed with a lateral projection normally extending into the corresponding vertical groove in said breech-housing and making a snug sliding fit therein and adapted to be snugly slidably received in its co-operating longitudinal groove in the opposed face of the breech block.

2. A sporting gun comprising a breech-housing having its opposed inner side walls formed with a pair of opposed longitudinal grooves, and a pair of opposed vertical grooves disposed in the same plane and respectively intersecting the respective horizontal grooves, in combination with a sliding breech-block formed with lateral ribs to be slidably received by the respective longitudinal grooves in said breech-housing and normally closing the breech end of said barrel element, said breech-block having its sides respectively formed with vertical grooves adapted to register in a transverse direction with the vertical grooves in said breech-housing, an operating lever mounted on said breech-block, a pair of locking keys connected to said lever to move therewith and respectively slidably disposed in the respective grooves in said breech-block, each said key being formed with a lateral projection normally extending into the corresponding vertical groove in said breech-housing and making a snug sliding fit therein and adapted to be snugly slidably received in its co-operating longitudinal groove in the opposed face of the breech-block.

3. A sporting gun comprising a breech-housing having its opposed inner side walls formed with a pair of longitudinal grooves, and a pair of opposed vertical grooves disposed in the same plane and respectively intersecting the respective horizontal grooves, in combination with a sliding breech-block formed with lateral ribs to be slidably received by the respective longitudinal grooves in said breech-housing, said breech-block having its sides respectively formed with vertical grooves adapted to register in a transverse direction with the vertical grooves in said breech-

housing, an operating lever, a pair of locking keys connected to said lever to move therewith in a direction at right angles to the lateral ribs, each said key being formed with lateral projections which, when the keys are moved to one position, register with said longitudinal grooves and, when the keys are lowered to another position, engage the walls of the vertical grooves in said housing to lock the breech-block against dis-	rigidly connected to said lever and respectively slidably disposed in the respective arcuate grooves in said break block, each said key being formed with a lateral projection normally extending into the corresponding arcuate grooves in said breech- housing and making a snug fit therein and adapted to be snugly slidably received in its cooperating longitudinal groove in the opposed face of the breech-block.	80
19 4. A sporting gun comprising a breech-housing having its opposed inner side walls formed with a pair of opposed longitudinal grooves, and a pair of opposed vertical grooves disposed in the same plane and respectively intersecting the respective horizontal grooves, in combination with a sliding breech-block formed with lateral ribs to be slidably received by the respective longitudinal grooves in said breech-housing and normally closing the breech end of said barrel element, said breech-block having its sides respectively formed with vertical grooves adapted to register in a transverse direction with the vertical grooves in said breech-housing, an operating lever mounted on said breech-block, a pair of locking keys slidably pivotally connected to said lever to move therewith and respectively slidably disposed in the respective grooves in said breech-block, each said key being formed with a lateral projection normally extending into the corresponding vertical groove in said breech-housing and making a snug sliding fit therein and adapted to be snugly slidably received in its cooperating longitudinal groove in the opposed face of the breech-block.	6. A sporting gun comprising a breech-housing having a pair of opposed generally vertically disposed grooves, in combination with a breech-block slidably mounted in said breech-housing, a spring-pressed hammer pin slidably mounted in said breech-block, an operating lever movably mounted on said breech-block, a pair of locking keys connected to said lever to move therewith and adapted in the lowest position of the lever to lock the block against movement in said housing, and in the raised position of said lever permitting sliding movement of said block in said housing, a bell crank lever pivotally mounted in said block and having its lower arm adapted to engage a shoulder of said firing pin to force the same rearwardly against the action of its spring and having its upper arm rearwardly presented, the said operating lever being formed with a finger underlying the upper lever of said bell crank and adapted to engage said lever and rock said bell crank about its fulcrum point to cock said firing pin as said operating lever is raised to free the said block for sliding movement, and spring means acting to depress said operating lever.	85
